DESIGN FOR A DRESS OR SIMILAR ARTICLE

Lillie Bernhard Starr, New York, N. Y.

Application July 23, 1937, Serial No. 70,587

Term of patent 14 years

To all whom it may concern:

Be it known that I, Lillie Bernhard Starr, a citizen of the United States and residing in New York city, in the county of New York, State of New York, have invented a new, original, and ornamental Design for a Dress or Similar Article, of which the following is a specification, reference being had to the accompanying drawing, forming a part thereof.

The characteristic feature of my design resides in the collar and cuffs of the particular configuration and in association with the dress shown.

I claim:

The ornamental design for a dress or similar article as shown and described.

LILLIE BERNHARD STARR.
